UNITED STATES PATENT OFFICE.

MALCOLM F. MCINTYRE, OF GIRARD, PENNSYLVANIA, ASSIGNOR OF ONE-HALF TO DAVID E. DAY, OF SAME PLACE.

BOSOM-BOARD.

SPECIFICATION forming part of Letters Patent No. 364,361, dated June 7, 1887.

Application filed December 13, 1886. Serial No. 221,469. (No model.)

To all whom it may concern:

Be it known that I, MALCOLM F. MCINTYRE, a citizen of the United States, residing at Girard, in the county of Erie and State of Pennsylvania, have invented certain new and useful Improvements in Bosom-Boards; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

My invention relates to bosom-boards; and it consists in the improvements hereinafter set forth and explained in the specification and claims.

My invention is illustrated in the accompanying drawings, in which Figure 1 shows a top or plan view of my improved board, with a bosom having the neckband broken away thereon. Fig. 2 is a view of a section thereof in perspective. Fig. 3 is a central cross-section of the same. Fig. 4 is a perspective view of the inside section of the neckband-support of my bosom-board. Fig. 5 is a like view of the outside section of the same.

Like letters refer to like parts in all the figures.

In the construction of my improved bosom-board I make the body A preferably of wood, with its lower end somewhat narrower at B than the upper end, C, and with the corners of the lower part, B, of the board cut away, so as to form the projection E thereon. The edges of the board A, I make nearly half-round from B to C, as illustrated in the cross-section, Fig. 3. Along these rounded edges I secure the clamping-strips F F by means of arms G G, pivoted to the board A by means of pintles g, inserted in the upper end, C, and in the shoulders B of the board, so that the clamping-strips F will swing entirely around the edges of the board from one side to the other, as illustrated in Fig. 3. The end e of the projecting portion E of the board is likewise rounded and provided with a clamping-strip, H, secured to the sides of said projection by means of arms I I, pivoted upon pintles i i in the edges of the projection E, so that the strip H

will swing around the end e from one side of the board to the other.

On each side of the board A and the projecting portion E thereof I secure pads or cushions J and J', as illustrated in Fig. 3, one of these cushions being preferably covered with fine white cloth in a manner suitable for the ironing of fine white bosoms thereon, while the other side may be covered with coarser cloth, so as to be suitable for the ironing of coarse or colored bosoms thereon, the side clamps, F F, and the end clamp, H, operating with equal facility for securing bosoms upon either side of the board.

To the central part of the upper end, C, of the board I attach a handle, P, which I make either of wire or of a flat strip of metal in the shape of a half-circle, projecting outwardly from the end C of the board.

To the central portion of the upper end, C, of the bosom-board I secure a removable neckband-support, D, by means of a clamp, K, secured thereto and adapted to slip over the end C of the board, by means whereof the neckband-support may be secured upon either side 75 of the board A, as desired. This neckband-support D preferably consists of a circular inside band, L, of spring metal, secured to a clamp, K, and adapted to fit inside of the neckband of a shirt and expand itself outwardly, 80 so as to fill a neckband placed upon it. Inside of this band L springs O O' are secured to the clamp K, the ends of which springs project through slots i i in the ends of the band L, so as to enter the button-holes in the back of a 85 neckband, the tension of these springs being inward, so that when the ends thereof are inserted into the button-holes of a neckband placed on the support the springs O O' operate to draw the neckband tightly around the 90 band L, the band L at the same time operating to expand it outwardly, the joint action of the band L and of the springs O O' operating to stretch the neckband tightly around the band L, without regard to ordinary variations in the 95 sizes thereof. The neckband-support D is also provided with a removable outside band, N, adapted to be clamped around the outside of a neckband when in place upon the inside supporting-band, L, so as to secure it firmly 100

in place thereon, this band N being provided with catches n, so arranged as to adapt it to fit different-sized bands.

In operation, the neckband of the shirt is first placed upon the neckband-support and secured thereto. Then the lower end of the bosom is drawn down and secured by the clamp H, the outside band, N, operating to prevent the neckband from being drawn out of place. After securing the lower end of the bosom the sides of the bosom may be stretched and secured by means of the side clamps, F F, when the bosom is ready to be ironed.

It is obvious to those skilled in the art to which my invention appertains that, as my device is constructed, the clamps F F and H will operate with equal facility for securing a bosom to either side of the band, and also that the neckband-support D is readily adjustable to operate on either side of the board.

Having thus fully described my invention, so as to enable others to construct and use the same, what I claim as new, and desire to secure by Letters Patent of the United States, 25 is—

1. The combination, in a bosom-board, of the rigid side clamps, F F, and end clamp, H, pivotally connected to and adapted to operate from either side of the board A, with a removable neckband-expander, L, provided with the springs O O' and the adjustable clamping-band N, adapted to clamp the neckband of a shirt to the expander L, substantially as and for the purpose set forth. 30

2. The combination, in a neckband-expander 35 for a bosom-board, of the circular metallic inside band, L, the springs O O', and the support therefor, D, with an adjustable clamping-band, N, adapted to be clamped around a neckband on said expander, substantially as 40 and for the purpose set forth.

In testimony whereof I affix my signature in presence of two witnesses.

MALCOLM F. McINTYRE.
